UNITED STATES PATENT OFFICE

101,029

DESIGN FOR A BOTTLE CAP OR SIMILAR ARTICLE

Joseph R. Fleisch, Clifton, N. J., assignor to Anchor Cap & Closure Corporation, Long Island City, N. Y., a corporation of New York

Application January 29, 1935, Serial No. 55,121

Term of patent 14 years

To all whom it may concern:

Be it known that I, Joseph R. Fleisch, a citizen of the United States, residing in Clifton, county of Passaic, State of New Jersey, have invented a new, original, and ornamental Design for a Bottle Cap or Similar Article, of which the following is a specification, reference being had to the accompanying drawing, forming a part thereof.

The figure is a perspective view of a bottle cap, showing my new design.

Dominant features of the design are a skirt ornamentation comprising a continuous band of relatively prominent ribs located close to each other and extending circumferentially about the skirt of the cap, the ribs being arranged in groups, said groups tapering from top to bottom on each

side thereby forming apices and troughs, the bottoms of the ribs being spaced substantially from the bottom of the cap by a zone slightly larger than the portion of the cap above the zone, and a cover ornamentation comprising ribs increasing in height to form apices and decreasing in height to form troughs adjacent the apices and troughs formed by the ribs on the skirt of the cap.

I claim:

The ornamental design for a bottle cap or similar article, substantially as shown and described.

In witness whereof, I have hereunto affixed my hand and seal, this 24th day of January, 1935.

JOSEPH R. FLEISCH.
